CLAIM

The ornamental design for a bushing, as shown and
described.

DESCRIPTION

FIG. 1 is a front perspective view of a bushing, showing
my new design;

FIG. 2 is a side elevational view thereof;

FIG. 3 is a rear end elevational view thereof;

FIG. 4 is a front end elevational view thereof;

FIG. 5 is a plan view of one of the two symmetrical
halves of the bushing shown in FIGS. 1-4, taken along
line 5—5 in FIG. 4;

FIG. 6 is a bottom plan view thereof;

FIG. 7 is a front end view of FIG. 5; and,

FIG. 8 is a rear end view of FIG. 5.

FIG. 1

FIG. 2

FIG. 3

FIG. 4

FIG. 5

FIG. 6

FIG. 7

FIG. 8
